PNEUMATIC CONTROL FOR WRAPPER TRANSFERS

Sigurd Clausen, Brooklyn, N. Y., assignor to International Cigar Machinery Company, a corporation of New Jersey

Application November 30, 1937, Serial No. 177,247

12 Claims. (Cl. 131—21)

This invention relates to improvements in pneumatic controls for cigar wrapper transfers. One of the principal objects of the invention is to provide simplified operating means for the flag pump of such a transfer as that illustrated in the patent to Halstead, No. 1,721,554, granted July 23, 1929.

Another object is to provide operating means for the flag pump which can be applied to existing cigar rolling machines with relatively little change or reconstruction of the machine, as by getting all the cam or timed motions from one face of a plate cam, such for instance as the cutter roller operating cam with which the machines are equipped.

It is, therefore, an object of the invention to provide a simplified construction in which no additional cams or cam shafts are required for the flag pump operation.

In this connection it is also an object to set the flag pump by crank means for subsequent tripping by cam means.

A feature of the invention is the arrangement of the foregoing to permit adjusting the time of tripping the pump to determine when the flag pump blast is applied.

Still another object is to provide an improved suction cutoff for cutting off suction in the suction transfer when the wrapper carrying face plate is removed, which will be more universally applicable than prior devices of this general type.

With these and other objects in view the invention consists in the constructions set forth and more particularly pointed out in the appended claims.

In the accompanying drawing:

Fig. 1 is a front view of a portion of the machine showing the pump and connection to the wrapper transfer and also illustrates the pump control mechanism;

Fig. 2 is a side view of the pump and control mechanism;

Fig. 3 is a detail plan view of the wrapper carrier unit embodying the improved suction control valve which closes when the perforated suction head is removed;

Fig. 4 is a sectional detail view of the valve unit;

Fig. 5 is a fragmentary view, in sectional elevation, of a schematic character, illustrating the wrapper transfer at the wrapping section; and

Fig. 6 is a detail view in vertical section on the line 6—6 of Fig. 3.

Referring to the drawing, the pneumatic control mechanism illustrated is used in conjunction with cigar machine mechanism for supplying a wrapper and applying it to a bunch B (see Fig. 5).

A revolving disk 10, Figs. 1 and 2, in the present invention is provided with a stud 11 mounted off center and imparting a crank motion to a link 12 connecting to an arm 13, loosely mounted on a stud 14 secured in a bracket 15 attached to the frame 40 of the machine. Arm 13 has an extending arm 17 equipped with a bolt 18 fastened to a lever 19 also pivoted on stud 14. The other end 20 of lever 19 is forked, as seen in Fig. 2, permitting the rounded or yoke end portion 20 of the lever to straddle the piston rod 21 and a trip lever 24, and to engage an actuator block 22 secured on said rod.

Lever 19, in depressing rod 21, moves the piston 23 to its lower position, where it is held by trip lever 24 provided with a latch 25 engaging the block 22. Lever 24, pivotally mounted on a stud 26 carried by frame 15, has an upwardly extending arm 27 supporting a cam roller 28 adapted to be engaged and tripped by a cam piece 29 during each cycle of disk 10. Arm 27, in being tripped, turns about its pivot 26 and swings trip lever 24 from its holding position, permitting a compression spring 30 (Fig. 2) to return the piston 23 to its up-position 31, as shown in dotted lines. The resultant air-blast passes through a flexible tube 32 connecting to a tube 33 leading to the wrapper carrier top 34 which directs the air downwardly, the blast passing through the perforated wrapper carrier bottom plate 35 and acting to blow the flag portion F of the wrapper leaf from plate 35 for reasons to be hereinafter described (see Fig. 5).

The piston 23 operates in a cylinder 36 which constitutes the upper portion of the pump housing 37. Housing 37 has a plurality of lugs 38 secured to bracket 15 by tie bars 39 carried by the frame 40 of the machine, the hubs 38 being secured to the bracket 15 by bolts 41. The piston rod 21 is guided in a bearing 42 of housing 37 and in a hub 43 of the downwardly projecting arm 44 of bracket 15.

The operation of the mechanism is as follows: Disk 10, in revolving, by means of crank pin 11 imparts motion to the lever 19 which moves the piston 23 to its down-position whereupon a trip lever 24 by means of latch 25 engages the actuator block 22 of the piston and holds the piston in the down-position (see Fig. 1). Lever 19 then ascends to its up-position 45, shown in dotted lines, Fig. 1, at which time the cam piece 29 engages cam roller 28, thereby tripping arm 27 which in turning about its pivot 26 releases latch plate 25 from block 22, permitting spring 30 to raise the piston to its up-position. During the elapsed

time, a wrapper leaf having been
cut, actuated by the system of

reference may be made to the patent to Tyberg, No. 1,075,172. The patent to Halstead, No. 1,721,554, also illustrates, in some detail, the structure of a suction control for cigar wrapper carriers upon which the present invention is to be regarded as an improvement.

In Fig. 6 is shown on an enlarged scale, taken on the line 6—6 of Fig. 3, an improved form of connection between the fluid-pressure pipe 33 and the head 34, this connection having a duct 68 in communication with a throat 69, the wall 70 of which is concaved to afford a smooth flow of the blast into the head 34 (see Fig. 5).

What is claimed is:

- 15 1. In a cigar wrapping mechanism of the class described, including a wrapper transfer for delivering a wrapper to the cigar wrapping devices, said transfer being provided with means for holding a wrapper in outspread condition thereon, and also including a single rotary disk connected with gearing adapted to operate other mechanism in a cigar making machine said disk being provided with a tripping means, a flag pump adapted to apply intermittently a blast effective 20 to blow the flag end of each wrapper successively from said transfer device; and means to control the operation of said flag pump, said controlling means comprising devices connecting said flag pump with said single rotary disk, said connecting devices including means adapted to set said flag pump for subsequent tripping by said tripping means on said disk.
- 25 2. In a cigar wrapping mechanism of the class described, including a wrapper transfer for delivering a wrapper to the cigar wrapping devices, said transfer being provided with means for holding a wrapper in outspread condition thereon, and also including a single rotor connected with gearing adapted to operate other mechanism in a cigar making machine; a flag pump adapted to apply intermittently a blast effective 30 to blow the flag end of each wrapper successively from said transfer device; and means to control the operation of said flag pump, said controlling means comprising devices connecting said flag pump with said single rotor, said connecting devices including crank means adapted to set said flag pump and means on said rotor for tripping said flag pump.
- 35 50 3. A flag-pump-operating mechanism having the features set forth in claim 2 in which provision is made of means to adjust the means for tripping said pump to vary the time when the flag pump blast is to be applied.
- 40 55 4. In a cigar wrapping mechanism of the class described, comprising a bunch rolling mechanism, a wrapper cutter mechanism, a suction wrapper-transfer mechanism whereby a wrapper is transferred under suction from said cutter mechanism to a bunch in said rolling mechanism, means for driving said mechanisms in timed relation, a single rotor having a face perpendicular to its axis, gearing connecting said face of the rotor with said driving means, a suction mechanism adapted to apply suction effective to hold each wrapper in its turn during transfer, means to apply a blast intermittently to blow the flag end of each wrapper successively from the transfer to said bunch, and operating 60 connections between said air blast mechanism and said rotor, said blast creating mechanism comprising a flag pump, and said rotor having said face connected to the flag pump by a crank device adapted to set said pump; a latch device 65 adapted to hold the piston of the pump in said

set position; means for tripping said latch when the flag pump blast is to be applied, and a cam means on the face of said rotor adapted to operate said tripping means.

5 5. A flag pump operating mechanism having the features set forth in claim 4 in which provision is made of means to adjust the means for tripping said pump to vary the time when the flag pump blast is to be applied.

10 6. A flag pump operating mechanism having the features claimed in claim 4 in which said flag pump comprises a cylinder provided with a top port, and which has a piston rod fitted with a collar plate so disposed on said rod relatively to the co-acting portion of the crank means, and so disposed with relation to the stroke of the piston within the cylinder, that the piston will always bottom against a cushion of residual air beyond said port in the top of the cylinder, and thus a certain amount of lost motion will be permitted to the crank arm relatively to the piston rod collar, such amount of lost motion between said co-acting parts being adequate to prevent injurious shocks therebetween regardless of adjustments of the latch tripping connections, and 15 means to adjust the position of said cam means upon said face plate to vary the time of tripping said latch, and thus to determine when the flag pump blast is to be applied.

15 30 7. A flag pump operating mechanism having the features claimed in claim 4 in which said flag pump comprises a cylinder provided with a top port, and which has a piston rod fitted with a collar plate so disposed on said rod relatively to the co-acting portion of the crank means, and so disposed with relation to the stroke of the piston within the cylinder, that the piston will always bottom against a cushion of residual air beyond said port in the top of the cylinder, and thus a certain amount of lost motion will be permitted to the crank arm relatively to the piston rod collar, such amount of lost motion between said co-acting parts being adequate to prevent injurious shocks therebetween regardless of adjustment of the latch tripping connections, and 20 means to adjust the position of said cam means upon said face plate to vary the time of tripping said latch, and thus to determine when the flag pump blast is to be applied, said cam means being 25 formed with an arcuate slot and provided with 30 fastening means passing through said slot into the face of said rotor.

35 8. In a suction head of the class described, for wrapper carriers, said head having a suction chamber, a detachable suction plate for carrying the wrapper, and a hollow neck by which said suction chamber is supported for transfer, the combination with said neck of means for automatically cutting off the suction when the plate is detached, said means including valve mechanism within said neck, means whereby the valve mechanism is normally incapacitated when the suction plate is attached, and means acting upon detachment of said plate to operate said valve mechanism to cut off said suction, said neck being detachable from said chamber, with said valve mechanism, as a unitary structure.

40 60 9. In a suction head of the class described, for wrapper carriers, said head having a suction chamber, a detachable suction plate for carrying the wrapper, and a hollow neck by which said suction chamber is supported for transfer, the combination with said neck of means for automatically cutting off the suction when the plate is detached, said means including valve mecha- 65 70 75

- nism within said neck, a spring pressed plunger mounted within said neck and projecting into position for engagement normally with said plate, whereby the valve mechanism is normally incapacitated when the suction plate is attached, and a spring acting upon detachment of said plate to bias said valve to cut off said suction, said neck being detachable from said chamber, with said valve mechanism, including said spring pressed plunger, as a unitary structure, for ready inspection, repair and replacement.
10. In a suction head of the class described, for wrapper carriers having a suction chamber, a detachable suction plate for carrying the wrapper, and a hollow neck by which said suction chamber is supported for transfer; the combination with said neck of means for automatically cutting off the suction when the plate is detached, said means including valve mechanism within said neck, a sleeve mounted within said neck, a plunger mounted to slide in said sleeve and projecting into position for engagement normally with said plate, whereby the valve mechanism is normally incapacitated when the suction plate is attached, and a spring mounted upon said plunger within said sleeve, and acting upon detachment of said plate to bias said valve to cut off said suction, said valve mechanism comprising a valve member and an arm extending from said valve member and connected pivotally to the upper end of said plunger.

11. A flag pump operating mechanism having the features claimed in claim 1 in which said single disk comprises a plate mounted upon the supporting frame of a cigar making machine and having a face, and said flag pump includes a cylinder mounted on said support in proximity to said disk plate face, and also a piston spring-

biased toward one end of the cylinder to create a blast, and having a piston rod extending through the other end of the cylinder and provided with a plurality of collars; said operating connections between said disk plate and piston rod comprising in combination a crank pin and a swinging crank on the face of said disk, a lever pivoted on said support and having an arm connected with the free end of said crank, said lever having a second arm with its free end adapted to be engaged with one of said collars in an intermediate position upon said piston rod, whereby said crank is adapted to set said piston rod outwardly against the bias of said spring; a lever pivoted on said supporting structure intermediate said flag pump and said face plate of the disk, one arm of said lever having formed therewith a latch member adapted to be engaged with a collar on said piston rod, to hold said piston rod in its extended set position, and another arm of said lever being extended across said face plate, and a cam means attached adjustably to said face plate, whereby upon rotation of said face plate said latch will be tripped at a predetermined time, variable at will, during each cycle of said cam plate.

12. In a suction head of the class described, for wrapper carriers, said head having a detachable hollow neck, a suction chamber mounted detachably on said neck, a suction plate mounted detachably on said suction chamber for carrying the wrapper, and means carried directly by said neck and extending through said suction chamber for automatically cutting off the suction when the plate is detached, said means including a valve, and valve control mechanism within said neck.
